VANITY CASE OR SIMILAR ARTICLE

André Courreges, Neuilly, France, assignor to Courreges Parfums, Paris, France

Filed Jan. 23, 1970, Ser. No. 21,052

Term of patent 14 years

Int. Cl. D28—02

U.S. Cl. D86—10

FIG. 2

FIG. 1 is a front elevation view of a vanity case showing my new design, the opposite side being substantially the same but without the lip, the bottom being flat and unornamented; and

FIG. 2 is a perspective view thereof in open position.

I claim:

The ornamental design for a vanity case or similar article, substantially as shown and described.
